United States Patent Office

Des. 217,799
Patented June 9, 1970

217,799

BAND TYPE CUTOFF SAW OR THE LIKE

Isamu Amada, 23-18 Higashinakano 5-chome,
Nakano-ku, Tokyo, Japan

Continuation-in-part of design application Ser. No. 6,658,
Apr. 12, 1967. This application Mar. 6, 1969, Ser. No.
16,188

Term of patent 14 years
Int. Cl. D15—05

U.S. Cl. D93—3

FIG.1.

FIG.2.

FIG.5.

FIG.4.

FIG.3.

FIG. 1 is a front view of a band type cutoff saw or the like embodying my new design;

FIG. 2 is a back view of the band type cutoff saw or the like as shown in FIG. 1;

FIG. 3 is a side view showing the right end thereof;

FIG. 4 is a side view showing the left end thereof, and

FIG. 5 is a top plan view of the band type cut off saw or the like as shown in FIG. 1.

The dominant features of my design reside in those portions illustrated in full lines.

I claim:

The ornamental design for a band type cutoff saw or the like, as shown and described.
